UNITED STATES PATENT OFFICE.

ITHAMER M. JONES, OF ELM MOTT, TEXAS.

CAR-COUPING.

SPECIFICATION forming part of Letters Patent No. 415,295, dated November 19, 1889.

Application filed August 9, 1889. Serial No. 320,237. (No model.)

To all whom it may concern:

Be it known that I, ITHAMER M. JONES, a citizen of the United States, residing at Elm Mott, in the county of McLennan and State of Texas, have invented certain new and useful Improvements in Car-Couplings; and I do hereby declare the following to be a full, clear, and exact description of the invention, such as will enable others skilled in the art to which it appertains to make and use the same.

This invention relates to car-couplings; and it consists in the novel construction and combination of the parts hereinafter fully described and claimed.

15 In the drawings, Figure is a plan view from above, partly in section, of the two halves of the coupling ready to be pushed together. Fig. 2 is a side view of the same.

20 A is a coupling-head provided with a stem *a* for attaching it to the car, and B is a coupling-socket, also provided with a stem *a* for attaching it to the reverse end of another car. The coupling-head A is provided with a central projecting tongue C at its front end, having the shoulders *c* for the front edges *b* of the socket B to strike against.

25 D are pockets formed in the coupling-head upon each side of the central tongue, and E are hooks having their rear ends *e* abutting against the bottoms of the said pockets. The pockets are wider than the ends *e* of the hooks, so that the hooks are free to move laterally, and F are pivot-pins, which retain the ends of the said hooks in the pockets. The front edges *f* of the pockets are beveled, and *g* are correspondingly - beveled shoulders on the hooks, which permit the ends of the hooks to be forced inwardly toward the central tongue and prevent the hooks from being forced too

40 far in the opposite direction.

H are springs secured by rivets *h* to the central tongue, and having their free ends bearing against the hooks and pressing them outwardly. Shoulders *i* are formed upon the 45 hooks E substantially in line with the shoulders *c* on the central tongue and for the same purpose.

I is a vertical spindle journaled in the central tongue, and *j* are flexible cords or chains 50 wound upon the spindle and secured to it at

one end and having their opposite ends secured to the hooks E. The vertical spindle may be revolved to wind up the chains and draw the hooks inward by means of any convenient form of handle applied to the top of it. 55

The coupling-socket is provided with a cavity J, and *k* are holes in the sides, which leave the catches *m* in the front of the coupling-socket for the hooks of the coupling-head to engage with. When the cars are pushed together, the beveled edges *m'* on the front of the hooks strike against the catches *m* on the socket and the hooks are pressed inward, entering the cavity and springing outward through the holes *k* as soon as their hooked front ends have passed the catches. The springs H keep the two halves of the coupling coupled together, and the shoulders *c* and *i* prevent the front ends of the tongue and the hooks from striking against the bottom of the 70 cavity J. The coupling-head is uncoupled from the socket by revolving the spindle I and winding up the chains or cords, so as to draw together the hooks until they clear the catches on the socket. 75

What I claim is—

1. In a car-coupling, the combination, with the coupling-head provided with a central tongue having shoulders *c*, and the spring-actuated hooks pivoted to said head on each 80 side of the tongue and provided with shoulders *i*, of the coupling-socket provided with a cavity having catches *m* at its sides for the said hooks to engage with, substantially as and for the purpose set forth. 85

2. In a car-coupling, the combination, with the coupling - head provided with a central tongue and a socket on each side of the tongue, and the forwardly-projecting spring-actuated hooks pivoted to the said head, with their rear 90 ends abutting against the bottoms of the sockets and provided with beveled front edges *m'*, of the coupling-socket provided with catches *m* for the said hooks to engage with automatically, and the vertical spindle journaled in the central tongue and provided with flexible connections wound upon it and secured to the hooks for drawing said hooks inwardly, substantially as set forth. 95

3. In a car-coupling, the combination, with 100

the coupling-head provided with a central tongue, and pockets on each side of the tongue having forwardly and outwardly projecting beveled edges *f*, and the spring-actuated hooks provided with ends pivoted in said pockets and with beveled shoulders *g* corresponding with said edges *f*, which limit their outward motion, of the coupling-socket provided with

catches for the said hooks to engage with automatically, substantially as set forth. 10

In testimony whereof I affix my signature in presence of two witnesses.

I. M. JONES.
